BATTING APPARATUS FOR BASEBALL GAMES AND THE LIKE

Original Filed Aug. 17, 1928

INVENTOR:
PARKER T. SIMMONS,
BY
H. Woodward,
ATTORNEY.

UNITED STATES PATENT OFFICE

PARKER T. SIMMONS, OF EAST HAMPTON, NEW YORK

BATTING APPARATUS FOR BASEBALL GAMES AND THE LIKE

Application filed August 17, 1928, Serial No. 300,238. Renewed July 11, 1930.

The invention has for an object to present an improvement in batting devices suitable for game boards and apparatus where games simulating standard outdoor games of baseball are played. It aims to present a batting device which may be constructed in an attractive and simple form, adapted to add realism to the game played, at the same time affording novel structure in the actuating and control mechanisms and conveniently operated by a player. It is an important purpose to enable the construction of the principal parts from sheet metal, so that a game of this kind of extensive proportions may still be commercially produced at a low cost.

The mounting device is particularly adapted for use in apparatus described in my pending application Serial No. 300,236, baseball game and apparatus, filed August 17, 20 1928, directed to apparatus for indoor baseball. Advantages and novelty of the invention will be understood from the accompanying description and drawings, wherein

Figure 1 is an elevational view of an apparatus constructed in accordance with my invention.

Figure 2 is a top view thereof.

Figure 3 is a detail of the latch and reset mechanism.

30 There is illustrated a portion of a game board floor 10, upon the under side of which there is secured a bracket 11 substantially U-shaped, the arms being turned outwardly and secured to the under side of the floor. 35 Centrally over this bracket a flanged ferrule or bearing collar 12 is secured to the floor and receives therethrough the upper end of vertical stud shaft 13 transversely slotted in its upper end and projected slightly above the 40 floor, being revoluble in the collar and also revolvably mounted upon the bight of the bracket in any approved way. The shaft has fixed upon its lower part within the bracket a disk 14 having peripheral latch and reset notches 15 and 16 respectively therein spaced circumferentially a proper distance. Loosely engaged around the shaft between the disk and collar 12 there is a helical torque spring 17 having its lower end engaged 45 through a suitable aperture in the disk so

that the spring may rotate the disk at times. The upper end of the spring is secured to the collar 12. The bight portion of the bracket is horizontal and planiform, and has pivoted thereon adjacent the disk a latch lever 18 having a bill 19 thereon adapted to enter the notch 15 when the disk and shaft are rotated to an initial set position against the torque of the spring, and a suitable spring 20 engaging the lever 18 acts to force it yieldingly into engagement with the disk. The lever projects a suitable distance from its pivot beyond the notch-engaging bill thereof and has connected thereto a link, cable or other operating means 21, provided with a finger piece 22 which may be located beside the game board to be operated at will by the finger of a player. Pivoted upon the shaft immediately over the disk and resting against the disk, where it may be held snugly by the axial contractile force of the spring 17 there is a reset arm 23. The arm projects radially beyond the disk a suitable distance. Pivoted thereon is a dog 24 which bears against the periphery of the disk 14 by the action of a spring 25 coacting between the arm 23 and dog. The spring in this instance is a short helical spring engaged around the pivot pin of the dog and having respective arms hooked over the back of the dog and over the edge of the lever so as to cause the dog to bear upon the disk. A contractile spring 26 is anchored upon the bracket and connected with the outer part of the reset arm 23, tending to hold it in initial position, while extending from the arm oppositely from the spring 26 there is a cord or cable 27, extended around a pulley 28 and thence to a reset finger piece 29 located near the finger piece 22. By pulling upon the finger piece 29 the cable 27 draws the arm a suitable distance, the dog engaging the reset notch 16 on the disk 14 to move the disk and shaft against the action of the spring 17 until the latch lever 18 may engage the release notch 15.

50 A batter body 30 is provided having a lower leg 31 formed with a suitable socket and key to engage over the exposed slotted end of the shaft 13 and to engage in the slot 55 therein so that the body will be rotated by 100

movement of the shaft. The body is also provided with a bat arm 32 at a suitable level and properly shaped to engage a small ball when thrown adjacent the device in accordance with the uses of such appliances. The body is also provided with an outer leg 33 having a foot portion 34 so located as to sweep closely over the floor 10 when the appliance is operated. At a suitable point upon the upper part of the floor there is secured a stop 35, which may be cushioned or resiliently formed, to check the movement of the batting device by engaging the foot 34 at the proper limit of operative movement. The lower part of the leg 33 may be shaped and constructed to flex slightly when engaging the stop and being formed of resilient material, the action of the device is thereby cushioned and quieted.

In the operation of the device, for playing a game, the reset finger piece 29 is operated to draw the batting device to initial position; and a ball then being properly delivered adjacent the device, the player operates the release finger piece 22, endeavoring to so time the action of the device that the bat arm 32 will strike the ball as desired.

When the bracket is removed from the lower side of the floor the shaft and reset lever may be detached without the use of tools or the dismounting of bearings. Its assembly is consequently greatly cheapened by simplification.

I claim:

1. A device of the character described comprising a floor, a shaft revolubly mounted therethrough, means to operate the shaft, a batter body carried by the shaft over the floor, a bat arm thereon, a leg member thereon having a foot positioned to sweep closely over the floor, and a stop on the floor to engage the foot at the limit of operative movement of the device.

2. The structure of claim 1 in which the leg is formed with a resilient flexible lower part adapted to yieldingly engage the stop to cushion the stoppage of the device.

3. A device of the character described comprising a mounting plate, a vertical shaft revolubly mounted thereon having a disk formed with two notches, a manually releasable latch positioned and operative to engage one notch when the device is in set position, a torque spring engaged with the shaft, a swingingly mounted reset dog operative to engage the other of said notches when the device is at the limit of operative movement, and manually operable means to move the dog against tension of the spring for resetting of the device.

4. A batting device for games of the character described comprising a floor, a bracket thereunder, a vertical shaft revolubly mounted on the bracket and projected through the floor, a disk on the lower part of the shaft

having two peripheral circumferentially spaced notches, a helical torque spring around the shaft having one end connected to the disk and its other end fixedly anchored, a latch lever pivoted adjacent the disk and having a bill to engage one notch therein when the device is in set position, manually operable means to operate the latch to release the disk, a reset lever pivoted on the shaft, a spring pressed dog on the reset lever engaging the periphery of the disk, and manually operable means to swing the reset lever.

5. The structure of claim 4 in which the disk is spaced from the lower end of the shaft, the lower extremity of the shaft being journaled in the bracket, and the upper projected through the floor without bracket bearing, said torque spring being axially compressed, whereby the shaft is thereby maintained in its bearing.

6. The structure of claim 4 in which the disk is spaced from the lower end of the shaft, the lower extremity of the shaft being journaled in the bracket, and the upper projected through the floor without bracket bearing, said torque spring being axially compressed, whereby the shaft is thereby maintained in its bearing, the reset lever being also confined between the torque spring and bracket.

7. The structure of claim 4 in which the disk is spaced from the lower end of the shaft, the lower extremity of the shaft being journaled in the bracket, and the upper projected through the floor without bracket bearing, said torque spring being axially compressed, whereby the shaft is thereby maintained in its bearing, a ferrule bearing being set in the floor around the shaft with its flange below the floor and pressed thereto by said torque spring.

In testimony whereof, I affix my signature.

PARKER T. SIMMONS.
